ABSTRACT OF THE DISCLOSURE

A pump having a rocker arm, hermetically sealed from outside the pump housing, for transmitting power to the pistons within a pump housing.

BACKGROUND OF THE INVENTION

Field of the invention

This invention relates to absorption refrigeration, and more particularly, to absorption refrigeration systems of the type which employ a pump for forwarding solution from the absorber to the generator of the system.

Description of the prior art

In aqua-ammonia absorption refrigeration cycles of the two-pressure variety, it is necessary to pump the aqua-ammonia solution from the low pressure region of the absorber to the high pressure region of the generator. When such cycles are applied to residential and small commercial air-conditioning duty, the entire system is manufactured as a factory assembly with the solution charge factory installed and the equipment is expected to have long, unattended service life. These conditions require that the solution pump design be simple, reliable, low in cost, and, most important, without any form of sliding contact mechanical seal which could leak aqua-ammonia solution or vapor.

My issued Pat. No. 3,271,976 described a type of pump that has been shown to meet these requirements. The design of pump described herein is an improvement over the pump described in Pat. No. 3,271,976, while at the same time embodying certain novel features.

The design of a suitable pump for forwarding weak absorbent solution from the absorber to the generator of an absorption refrigeration system of the type which employs ammonia as a refrigerant and water as an absorbent, presents a number of special problems. In particular, typical head pressure requirements for such a pump substantially exceed that which can be satisfactorily achieved with a centrifugal pump. Vane and gear type pumps for this service would be required to operate at a high speed and could not be lubricated satisfactorily with water, and an oil lubrication system would be unsatisfactory due to emulsification of the oil with absorbent solution. They are also unsatisfactory due to cavitation, vapor binding and exhibit high rates of wear due to low lubricity of the solution being pumped and due to abrasive particles that cannot be entirely eliminated from the system. It is therefore desirable to employ a reciprocating pump for such application because they have a positive displacement, and can operate satisfactorily to produce high head pressure at slow speeds where lubrication with water can be satisfactorily achieved.

In a typical air-cooled, ammonia-water absorption system, the high side or pump discharge pressure may be on the order of about 300 pounds per square inch gauge and the low side or pump suction pressure may be on the order of about 50 pounds per square inch gauge. During operation of the system, the internal pressures in the pump crankcase may be either above or below atmospheric pressure. On shutdown of the system, the system may typically equalize at a pressure of about 200 pounds per square inch gauge.

2

Since ammonia is toxic, it is necessary that the pump be fully hermetic and leak proof in spite of the wide variations in internal pressures to which it may be subjected. One approach to providing the required degree of leak tightness is to employ a so-called "canned" hermetic motor within the pump casing. However, this approach is not suited for relatively small size absorption refrigeration systems of the type which might be employed to cool a residence, or small business establishment, because of the cost of such an arrangement.

10 Absorption refrigeration systems, of the type described, normally utilize a fan for passing air over the evaporator and condenser. It would be desirable to use the electric motor driven fan to operate the solution pump. However, 15 such an arrangement requires the use of a solution pump having an external seal because the fan motor must be outside the pump housing. The seal of conventional pumps is highly vulnerable to leakage and such pumps have proved unsatisfactory for the application described. For 20 example, rubbing type seals always permits some small amount of leakage to occur which may become excessive in time, particularly in a system employing ammonia, where even a small amount of leakage is objectionable and where the internal pump pressure is substantially above 25 atmospheric pressure on shutdown. Elastomeric seals have previously required bonding to the pump shaft and housing. However, it is virtually impossible to provide a satisfactory seal between an elastomeric seal member and a metal shaft or housing by the use of adhesives alone in 30 an aqua-ammonia system, and clamped seals are difficult to retain in position due to the extremes in pressure to which they are subjected in this application.

SUMMARY

As contrasted with the prior art, described above, the present invention provides a novel pump designed to include particularly: (a) the method of sealing and mounting the rocker arm 1 through which the mechanical power is transmitted hermetically from outside the pump housing to the pistons within the housing, (b) the method of mounting the piston within the pump housing, and (c) the means by which the effective displacement of the pump may be adjusted to meet the requirements of the system. These and other novel aspects of the design will be evident from a description of the following drawings.

BRIEF DESCRIPTION OF THE DRAWING

FIG. 1 shows a vertical section through a single cylinder version of the pump showing the rocker arm seal 3 and one means of mounting the pump cylinder.

50 FIG. 2 is a horizontal section taken at A—A of FIG. 1, showing the method of mounting rocker arm 1.

DESCRIPTION OF THE PREFERRED EMBODIMENTS

55 Referring to the drawings in detail, the pumping process employed is similar to that of a typical plunger pump. The particular design shown utilizes a ported cylinder 14 and conventional ball check discharge valve 27. The novel features of the design are equally well adapted to pumps with hollow ported pistons and with conventional suction and discharge check valves and no ports in cylinder or piston. In the embodiment shown in FIG. 1, the fluid being pumped enters housing 19 through pipe 18. In an 60 absorption system such as shown in earlier Pat. No. 3,271,976, housing 19 can serve as a collection chamber for the solution leaving the absorber and a space for the accumulation and purging of hydrogen and other non-condensables which must be removed from the system 65 periodically.

70 A body of the fluid 17 is present as a liquid in housing 19. The level of the liquid surface may be quite variable

depending on the rate of flow in through pipe 18, and the quantity delivered by the pump out through check valve 27 and discharge pipe 28. On each upward stroke of piston 15, its lower end reaches elevation 33 uncovering port 16. Liquid fills the space within the cylinder below piston 15, with flow taking place from the time the piston uncovers the lower edge of port 16 on the upward stroke until it is closed again on the downward stroke. When port 16 has been covered, the volume of liquid below the piston 15, in passage 39, and the cavity formed by the lower surface of port 22 and cover 26 is trapped and effectively sealed against return to space 17 by O rings 40 and 41. Further downward motion of the piston compresses and pressurizes the fluid to above the pressure in line 28. Check valve 27 opens and a quantity of fluid is discharged to the high pressure part of the system to which the pump is applied.

When piston 15 reaches its most downward position 34, flow through ball check 27 stops and spring 42 seats the ball. Upward movement of piston 15 results in a low pressure inside cylinder 14 which reaches its minimum value just as port 16 is uncovered. This contributes to rapid recharging of the space below the piston, and the cycle is repeated. It will be noted that holes 25 are provided in spacer 23 to enable the fluid during the downward stroke of piston 15 to flow out of cylinder 14, through channel 39, through said holes 25 and ball check 27, to discharge line 28.

Referring now to the novel mechanical details of the disclosure, it will be understood that one objective of the design is to provide adjustment of the effective pump displacement without changing the diameter or stroke of the piston.

A second objective is to minimize the number of bearings that are inside housing 19. This is particularly important in aqua-ammonia absorption systems where the only lubricant available, aqua-ammonia liquid, has relatively poor lubricating qualities.

A third objective is to minimize the number of openings required to assemble the internal parts of the pump. A fourth objective is to obtain a maximum piston stroke while at the same time limiting the stress level due to bending of rocker arm 1, the size of the opening in nipple 29 through which the rocker must enter housing 19, and the diameter and bending stress of the elastomeric seal 3.

The first objective is accomplished in two ways. It is to be understood that the number of up and down strokes per minute, and the total travel of push rod 11 are fixed by the revolutions per minute of the shaft, not shown, and the throw of the eccentric or crank, not shown, attached to said shaft and driving said push rod. Within limits, turning push rod 11 out of clevis 12 and relocking jam nut 10 raises the center position of bearing center 31 and the extremes of piston stroke 33 and 34. Since the lower edge of port 16 is unchanged, the effective displacement per stroke, the ported pump design is reduced. Second, with the push rod adjustment fixed, the addition of shims 21 and removal of a corresponding thickness of shims 24, will lower the cylinder 14. This reduces the distance between the lower edge of port 16 and extreme piston position 34 and reduces the effective displacement. Conversely, adding shims 24, and removing shims 21, increases displacement.

The second objective is achieved by the method of mounting rocker 1 on bearings 5, which are housed in a yoke-like structure 2, which projects toward the opposite end of the rocker from its point of attachment to the rocker while remaining outside of seal member 3. This provides a fulcrum 30 about which rocker 1 oscillates, using bearings that can be oil or grease lubricated rather than an internal bearing lubricated by the fluid pumped.

The third objective is achieved by inserting the piston and cylinder into the housing 19 from below along centerline 32, and placing clevis 20 over journal pin 31 after rocker 1 has been entered through nipple 29, and sealed

with elastomeric closure 3 by means of clamps 8. This eliminates the need of sliding seals of any kind and requires only one bolted cover 26 to close the housing 19.

The fourth objective is achieved by locating fulcrum 30 between the ends of tubular elastomeric seal 3 and providing a generally conically contoured rocker 1. The maximum bending moment in rocker 1 occurs where it is attached to yoke 2 in plane 43—43. The moment reduces toward the end of the rocker engaging clevis 20 so that the diameter of the section can be reduced without exceeding allowable design stress. By observing the dotted representation of the topmost element 35 of the rocker, as it is rotated clockwise to centerline position 37, it is evident that the portion to the right of fulcrum 30 moves down while that to the left moves up. The result is that the element becomes generally parallel to an element of tubular nipple 29. At the same time, the bending stress of tubular seal 3 is minimized and easily fabricated parts, such as rocker 1, nipple 29, and seal 3 result. It is to be understood that rocker 1 could be an integral part of structure 2 rather than being joined and secured by spring pin 13. Likewise, clamps 8 are only one means of joining seal 3 to rocker 1 and nipple 29. Crimped ferrules, flanges nuts and other means, known to the art of joining hose to terminal fittings, may be used with equal or better effectiveness.

A novel feature of the design disclosed is the method of mounting and positioning the cylinder. It will be recognized that the centerline of pin 31 follows an arc of a circle around fulcrum 30. Thus, the centerline 32 of piston 15 and cylinder 14 must rotate a small amount either side of some average position around a point located approximately at 44. By design, when the piston is in mid-position shown, centerline 32 is slightly to the left of mean position whereas when extreme positions 33 and 34 are reached, centerline 32 is slightly to the right. Such an oscillating cylinder is not novel, but it does permit the rigid attachment of piston 15 to clevis 20. It also would permit the use of an integral part instead of two parts 15 and 20 secured by spring pin 45. Such an integral part could, for example, be made from molded carbon graphite, which would provide good bearing properties for contact with cylinder 14 and pin 31.

It will be noted that the upper surface of 22 is generally spherical providing relief from the flat surface of the mating flange 46 on cylinder 14. Also, during the upward stroke of piston 15, a lower pressure will exist in the cavity below 22, than that above 22, the latter being in essential communication with space 17. Part 22 will be forced down by a small amount of clearance, which is left in the stack of shims 24, spacer 23, part 22, the thickness of flange 46 and shims 21. This will release cylinder 14 and allow it to rock. On the downward pressure stroke, part 22 will be forced upward by the pressure difference across O ring seal 40, and cylinder flange 46 will be firmly clamped against shims 21. However, the clamping will be of the type of an hydraulic spring so that the resistance to rocking of cylinder 14 is limited. It is evident that this provides positive positioning of the cylinder while still allowing the required oscillation, and is superior to a mechanical attachment of any kind.

While the description given refers primarily to a liquid pumping means, many of the novel details are applicable to similar devices, such as gas and vapor compressors. It is not intended therefore that any limitation is implied by the means described.

I claim:

1. In a hermetic system an hermetic pump or compressor comprising a hermetically sealed housing, said rocker arm extending through said housing from outside a hermetically sealed housing containing the fluid to be pumped into said housing containing said fluid, a fluid tight flexible tube, having one end attached to said rocker arm, and the other end attached to said housing, and wherein said flexible tube serves as a closure for the hermetic sys-

tem allowing mechanical motion to be transferred from outside the hermetic system to a piston inside the hermetic system, said rocker arm being fulcrumed outside of said fluid-tight tube.

2. An hermetic pump or compressor, as described in claim 1, wherein the axis around which said rocker arm oscillates, is established by a yoke-like extension to said rocker arm which contains bearings located on a centerline essentially at right angles to said rocker arm, and located generally between the area of attachment of said flexible member to said rocker arm and the area of attachment of said flexible member to said housing.

3. An hermetic pump or compressor, as described in claim 1, wherein the mechanical power required to pump the fluid in said hermetic system is applied to the end of the rocker arm outside the hermetic system at a point beyond the area of attachment of said flexible member, and wherein the pump pistons, piston rods, or other mechanical parts used to impel the fluid in the hermetic system are attached to the opposite end of said rocker arm.

4. An hermetic pump, as described in claim 1, in which the mechanical power is transferred to a piston within the hermetic system by means of an orbital motion of said rocker arm about a center located generally between the areas of attachment of said flexible member to said rocker arm and said housing, and wherein said center is established by a bearing, housed within yoke-like, or cup-like, extensions of said rocker arm attached to the portion of said rocker arm projecting outside of said hermetic system.

5. An hermetic pump, as described in claim 1, wherein

the cylinder is secured at one end by clamping of a flange-like extension and wherein the clamping force is provided by the hydraulic pressure produced by the pump piston acting on one of the clamping parts which itself acts as a piston.

5 6. An hermetic pump, as described in claim 1, in which the cylinder is secured at one end by clamping of a flange-like extension of said cylinder between a fixed part and an axially moveable part which acts like a hydraulic piston to position and force said flange-like extension of the cylinder against the fixed part.

10 7. An hermetic pump, as described in claim 1, in which two stacks of shims, in cooperation with a flange-like extension of the cylinder and parts between which said 15 flange-like extension is clamped, serve to locate the ports in the cylinder in relation to the extremes of the piston travel so as to effectively establish the displacement of the fluid during each stroke of the piston.
